UNITED STATES PATENT OFFICE.

ALEXANDER RECHNITZER, OF VIENNA, AUSTRIA-HUNGARY.

SETTING AND ADJUSTING MECHANISM FOR CALCULATING-MACHINES.

1,189,288.

Specification of Letters Patent.

Patented July 4, 1916.

Application filed July 31, 1911. Serial No. 641,427.

To all whom it may concern:

Be it known that I, ALEXANDER RECHNITZER, manager of the Autarit-Gesellschaft m. b. H., a subject of the Emperor of Austria-Hungary, residing at Vienna, Austria-Hungary, have invented a new and useful Improvement in Setting and Adjusting Mechanism for Calculating-Machines, of which the following is a specification.

10 The present invention relates to a new setting and adjusting mechanism for calculating machines, that is, a mechanism provided with means for setting up a figure, and adapted to transfer the figure set up once or 15 several times to a suitable counting gear or accumulator.

The invention is a part of a calculating machine, which forms the subject of a later application filed July 26, 1912, Ser. No. 20 711,622. But, it can be used in any calculating machine, for instance in that forming the subject matter of my prior application filed February 21, 1910, Ser. No. 545,193, or it may also be used in any other non-automatic calculating machine.

25 The objects of the improved construction are to build a durable and easily operated mechanism for transferring the figures set up, to the counting gear.

30 Another object of the invention is to construct transferring and setting means which can be adjusted automatically according to the figure which has appeared in any suitable manner in the counting gear and which figure shall be retained in the counting gear 35 while it is transferred to the setting means.

Another object is to construct the transferring mechanism and its setting means in such manner that a new figure can be set up 40 by the operator on the setting means, while the transferring means may still be, once or repeatedly, transferring another figure which had formerly been set up upon the setting means.

45 With these and other incidental objects in view, the invention consists in certain novel features of construction and combinations of parts, the essential elements whereof are recited in the appended claims, and a preferred 50 form of embodiment of which is described in detail hereinafter and fully illustrated in the accompanying drawings forming part of this specification.

In the accompanying drawings, Figure 1 55 is a cross-section through the setting mecha-

nism; Fig. 2 a longitudinal section; Figs. 3 and 4 show the right and left lateral plates respectively with the driving mechanisms for the setting mechanism; Fig. 4a is a detail of some of the parts less fully shown in Fig. 4; 60 Figs. 5-7 show the key mechanism in longitudinal section, cross-section and plan respectively; Fig. 8 is a detail view; Figs. 9 and 10 show the setting mechanisms in different positions, and Figs. 11-19 are detail views. Fig. 20 is an enlarged longitudinal section, showing details; Figs. 21-29 are diagrams to illustrate the principle of the working of the transferring means to the counter. 65

As the object of the present invention is 70 only to provide a calculating machine setting mechanism which can be substituted for the setting mechanism of almost any other known calculating machine, as much only of the other mechanisms of such machines 75 has been shown as is necessary to explain the driving and adjusting connections between the setting mechanism and the other machine. Most of those machines have a hand or motor driven main shaft from which all 80 other movements are derived. Such a shaft 3 is shown (Figs. 1, 3, 4, 11-14), by the rotation of which the feed gear is operated to transfer a figure set up in the bank of keys 17 (Fig. 1) to a counting gear or accumulator, which may be formed by a set of 85 numeral wheels 1c (Fig. 1), between which any known carrying mechanism may be arranged and which may be driven by means of gears 1a, 2a, through a gear 52, which 90 belongs to the setting mechanism presently to be described, and which therefore must be turned different amounts, depending upon the figure set up in the keys 17.

It is of advantage that the setting mechanism be so constructed as to allow it to be bodily moved as a whole along the counting gear. Then the setting mechanism can quickly be slid to different digits of the counting gear, which is of advantage in 100 many operations, especially in multiplications and division. Therefore the setting mechanism is constructed, independently of the other machine, with its own frame, formed between two lateral plates 9 and 10 105 (Figs. 3 and 4). The frame is slidably mounted upon four rods 4, 5, 6 and 7, (Fig. 2, also Figs. 1, 3 and 4) through the medium of which rods the necessary movements are also imparted to the different mechanisms, 110

as will be described later on. The two frame plates 9 and 10 (Figs. 3 and 4) are connected together by means of four rods 11, 12, 13 and 14, and between the rods is mounted as a main girder the key bridge 15 formed from a piece of sheet metal (Figs. 1, 5, 6 and 7). The key bridge carries in stamped out slots 16 nine suitable parts 17, bent to form keys and covered at the upper ends with caps 18 carrying Figs. 1-9 having the said figures printed thereon in accordance with their value. Along the keys 17 is mounted a slide 19 provided with nine slots 20 (Fig. 8). With each of these slots can engage the corresponding pin 21 of the keys, and the pins are generally in the positions shown in Fig. 8. When any one of the keys is depressed, the slide 19, situated under the same, is pushed to the left in Figs. 7 and 8, as the pin 21, moving down in the slot 20, must push the corresponding slide to the left. (See dotted lines, Fig. 1). In this way, a ratchet tooth 22 provided on the slide, shown also in Fig. 8, is moved out of the path of the teeth of a ratchet wheel 23 secured to a spindle 24. This tooth 22 forms part of an oscillating member 310 pivoted to the slide 19 (Fig. 2) as hereinafter more fully described. Thereby the tooth 22 is adapted to move longitudinally with the said slide and to oscillate in a plane at right angles thereto. The spindle 24 is exposed to the tension of a spring 25 (Fig. 6) which pulls down a toothed rack 26 adapted to rotate the spindle 24 by means of a pinion 27 thereon. To the spindle 24 is secured a toothed wheel 28 which, by means of a toothed wheel 29 rotates the resetting spindle 30 arranged under the heads of the keys and provided with pins 31. When the spindle 30 is rotated a pin 31 will press the pin 32 of the depressed key 17 and raise the key again into normal position. The pins 31 are secured to the resetting spindle 30 in such a way that, according to the value of the key, they will bring the depressed key back into the position of rest earlier or later, that is to say, after a greater or less rotation of the spindles 24 or 30. The spindle 24 will accordingly be locked after a greater or less rotation, for when the depressed key 17 moves back, the pin 21 of the said key, sliding upward in the slot 20, will again force the slide 19 to the right, and will also bring the ratchet tooth 22 into operative position relatively to the ratchet wheel 23, whereby the spindle 24 will be locked. The mechanism thus described shows clearly that, according to the key which is depressed, the spindle 24 will make a greater or less rotation, and then be locked. On the spindle 24 is mounted a cylinder 33 which has a groove 34. With the said groove engages a pin 35 (Fig. 9) and Figs. 21 to 29 of a double-armed lever 36 (dot pointed in Figs. 21-29)

which is pivotally secured to a sliding part 38 by means of a pivot pin 37 (Figs. 5, 7, 9 and 10). The other arm 39 of the double-armed lever 36 is pivoted by means of a pivot pin 40 to one end of a lever 41 dotted in Figs. 21 to 29, the other end of which is pivoted by a pivot pin 42 to an arm 43. (Best shown in Fig. 10; also in Fig. 9, and shown in full lines in the diagrams Figs. 21 to 29.) The arm 43 is screwed fast to a square oscillating spindle 44 journaled in bearings 45 and 46 in the lateral plates 9 and 10 (Figs. 3 and 4). When the spindle 44 is rocked from the main spindle, in the manner hereinafter described, the oscillation of the spindle 44 will, by means of the rods 43, 41, 39, bring about a movement of the sliding part 38 to a different extent, which extent from left to right of Figs. 9, 10 and 21 to 29, varies according to the position of the double-armed lever 36 during such oscillation. This position of the lever 36 will not change during a movement of the sliding part 38 as the grooved cylinder 33 which is guided on the spindle 24 by means of a spline and groove, must at the same time participate in the movements of the sliding part 38, so that during the movement the position of the double-armed lever 36 is not modified relatively to the sliding part 38.

The sliding part 38 with its rod 47 (Figs. 1 and 2) supported in the two rods 12 and 14 already referred to, is, in its turn, slideable in a horizontal direction, that is to say, parallel to the spindle 24. As shown in Fig. 1, the pin 40 forming a fulcrum is situated, in the position of rest of the lever 36, in a recess of the square spindle 44, so that the said fulcrum coincides with the center of rotation of the spindle 44, see diagram Fig. 21 and when the spindle 44 is rotated, no movement of the double-armed lever 36 is produced see diagrams Figs. 22 and 23. The farther the pivot 40 is moved away from the center of rotation of the spindle 44 however, owing to the action of the grooved cylinder 33, the greater will be the movement given to the sliding part 38 with the same oscillation of the spindle 44. In the diagrams, Figs. 21 to 29 are the depths to which the pivot 40 will fall upon the depression of any of the keys 1-9 and the length of way it will consequently be moved during an oscillation, indicated by dotted lines. If, for instance, a key 6 be depressed, the double armed lever 36 will first be moved in described manner, by the rotation of the grooved cylinder 33 into a position illustrated in the diagram, Fig. 24. Thereafter, during any oscillation of the square spindle 44, the pivot 40 and with it the sliding part 38 will be slid to the right (diagrams 25, 26) and back to the left along the dotted line marked "6" on the scale of the dia-

grams. The diagrams 27 to 29 illustrate the same movements if a key "9" is depressed. Each of the said sliding parts 38 carries corresponding toothed racks 48 and 49 (Figs. 1 and 10) which, by means of suitable toothed gears 50, 51, 52, (Fig. 1) transmit a greater or less rotation to the counting gear, according to the value of the depressed key. It is obvious that in this construction 10 it is necessary to have for each place value of the setting mechanism one series of keys and one set of lever mechanism herein described, all of whose levers can be driven from one and the same bar 44 oscillated in a 15 suitable manner. As the resetting spindle 30 makes a different rotation according to the value of the figure set, the wheel 53 secured to the spindle 30, Fig. 1, and indicating the key struck, shows the figure set 20 at the time.

The oscillation of the bar 44 is effected at each rotation of the main spindle 3 in the following manner, reference being had to Fig. 3. On the end of the main spindle 25 3 is mounted a crank pin 60 to which is pivoted a lever 61, which is therefore oscillated at each revolution of the main spindle 3, to the right and to the left in Fig. 3, and at the same time oscillates to a corresponding extent the lever 62 and the grooved rod 5. As already stated, the rod 5 (Fig. 1) is one of the rods on which the setting mechanism is slidably mounted in the casing of the machine. An arm 63 mounted on the 30 setting mechanism slides with the same, and is adjustably mounted on the spindle 5 by means of a spline and groove, so that it will also be moved by the oscillating movement of the spindle 5, which upon rocking will in its turn rock the bar 44 by means of the 35 rod 64 and the lever 65 secured to the bar 44. At each revolution of the spindle 3, the bar 44 will be rocked forward and backward to a given extent which can be determined at will. A mechanism which will now be described prevents a transmission to the counting gear during the return oscillation of the bar 44.

At each revolution of the main spindle, 40 the spindle 4 will be oscillated in a given manner, namely either to the right or left of Figs. 3 and 11, and then into the position of rest, by means of the following mechanism: Upon the main spindle 3 there is guided by means of a spline and groove 45 a sliding sleeve 66 (Figs. 11 and 12), carrying two cam disks 67 and 68 at one of its ends. The disks travel between double arms 69 and 70. Each of these two double arms carries at both ends a roller 71, 72, 73 and 74 which can slide on the disks. Roller 74 is covered by the roller 71, in Fig. 11. According as the sleeve with the two cam disks 67 and 68 is pushed to the right or to the 50 left of Fig. 12, the right or left pair of roll-

ers 73, 74 or 71, 72 will cooperate with the corresponding disks 68 or 67, the disks being of such shape that the levers 70 or 69, mounted to rock on the spindle 75, are moved first to the right and then to the left 70 according as the disks 68 or 67 acts on the corresponding pair of rollers. In this way there is produced a movement to the right and back, or to the left and back, which is transmitted by a projection 77 and lever 78 75 to the grooved spindle 4. To the grooved spindle 4 is secured (Fig. 3) a cast part 79 connected to the setting mechanism which part will be rotated by the spindle 4 (Figs. 3 and 15) and will be oscillated at each 80 revolution of the main spindle either to the right or to the left, and then back to the position of rest.

On the cast part 79 is mounted a drum segment 80 provided with a cam-groove 81 85 which moves a lever 82 at its point of engagement 83, to the right and left of Fig. 15, about its fulcrum 85, that is to say the lever 85 will be oscillated either to the right or to the left, according as the segment 80 90 is turned in one or the other direction. The lever 82 in its turn and by means of the pin 87 and groove 88 moves the spindle 90, on which are mounted the toothed wheels 50 (Fig. 1) so that the latter are moved to 95 the right or to the left, and thus brought into engagement either with the upper toothed rack 48 arranged at the right, Fig. 2, or with the bottom toothed rack 49 arranged at the left, Fig. 2. The toothed 100 wheels 50 will therefore be given a suitable rotation in one or the other direction by the setting mechanism already described, by means of the toothed rack 48 or 49, and the toothed wheels 51, connected to the 105 toothed wheels 50 by means of a sleeve, will therefore transmit the corresponding rotations by means of toothed wheels 52 to the counting gear, either in accordance with addition or with subtraction. It will thus 110 be clear that the question whether addition or subtraction is performed, is determined in the present construction by the segment 80 being oscillated either in one or in the 115 other direction, which is again determined by the corresponding oscillations of the levers 70 or 69 (Fig. 11) which are oscillated in a different manner according as the sleeve 66 with the two cams 67, 68, is moved to the right or to the left. During the second half of the revolution of the main spindle 3, the spindle 90 with the toothed wheels 50 is brought back to the initial 120 position, that is to say, out of engagement with the toothed racks 48 or 49, so that the return movement of the toothed racks 48, 49 is not transmitted to the toothed wheel 50. In the case of a machine operated by hand, the position of the two cam disks 68, 67 is determined by means of some well 125

known device, perhaps by arranging a sliding button directly on the sleeve 66.

Fig. 3 shows that the cast part 79 may be provided at the top with two projections 91, 92, for the purpose of accurately adjusting the bar 44. At each oscillation of the cast part these projections will press the lever 95 pivoted at 96 upward, by means of the bent end 93 of the said lever, so that 10 the pin 97 on the said lever 95 momentarily enters the corresponding recesses 98 provided on the cast part 98' screwed to the bar 44. In this way the bar 44 is locked at the beginning and at the end of each movement. It must be pointed out that the oscillation of the cast part 79 is effected by its driving mechanism substantially always at the beginning of the oscillations of the bar 44, that is to say, at a moment when the 20 oscillations of the said bar by the crank drive 60, 61 are practically zero.

The spindle 6 (Figs. 2 and 4) on which the setting mechanism is adjustably mounted, is also used as a driving spindle 25 for certain mechanisms of the setting mechanism which have to be operated. The spindle 6 is driven from the main spindle 3 in the following manner, illustrated in Figs. 13 and 14. On the spindle 3 is 30 mounted by means of a spline and groove a sleeve 100 to which are secured two disks, namely a circular disk 101 and a cam disk 102. If the sleeve is pushed into a position such as shown in Fig. 14, the front or cam 35 disk 102 will coöperate with the two rollers 103 and 104 of a double-armed lever 105 mounted on the spindle 75, in such a manner that the said lever 105 will be given a suitable rocking movement which it will 40 transmit by means of the tooth 106 and the lever 107, to the spindle 6. The cam 102 is given such a shape that at the beginning of a rotation of the spindle 3, the roller 103 is first forced a little to the right, and after 45 about half a revolution, is suddenly shifted to the left. The corresponding movement is transmitted by means of the spindle 6 and of the sleeve 109 (Fig. 4) sliding on the same, by means of the lever 110, 110' to 50 the oscillating part 111 secured on the through spindle 112. The oscillating part 111 has a groove 113 (Fig. 4) with which engages a pin 114 secured to an oscillating part 115 pivoted by means of a screw 116 55 to the wall 10 and oscillated accordingly about the pivot 116. The corresponding movement of the oscillating part 115 is transmitted by means of one arm 117 of the said oscillating part, provided with a bent 60 end 118 (Fig. 2) with a slot, and by means of a pin 119 engaging with the said slot, to an oscillating part 120 (Fig. 2) which is pivoted by means of a screw 121 to the usual through bar 12. 65 The oscillating part 120 is pivoted at its

lower end by means of a pin 122 to a bar 123 which accordingly is moved horizontally, as shown in Fig. 2, to the right and left. To the bar 123 are pivoted by means of pins 125, oscillating parts 124 adjustably mounted, by means of a spline and groove, on the previously described spindle 47, (Figs. 1 and 2) so that when the bar 123 is oscillated, the spindles 47 will be rotated.

The spindles 47 are provided with pins 126 passing through slots 127 stamped out in the sliding part 38 (Fig. 1) and acting as driver pins, so that the spindle 47 participates in the movements of the sliding part 38. These pins 126 project however at the same time through a slot 129 of a so-called locking device 130 which is adjustable by means of two screws 131, 132 in slots 133 arranged on the sliding part 38. The shape of the slots 129 and of the cam disk 102 (Fig. 4) is calculated in such a manner that at the beginning of each movement of the main spindle 3, a movement to the left of the locking device 130 takes place, according to Fig. 1.

The locking device 130 is provided at its left hand end with notches or recesses 140 and is arranged in such a manner that when it is moved to the left, the said recesses engage with a pin 141 (Figs. 1 and 9) secured to the lever 41, on the position of which depends the value of the number transmitted to the counting gear. The lever 41 is in this way locked in its particular position by the locking device 130, so that an accidental movement cannot take place. In Fig. 1 the locking device is shown in locked position, from which position it is moved to the right for unlocking the pin 141.

It is necessary that, when an addition is being performed and the proper setting has been made, the setting mechanism should remain locked only during one revolution of the main spindle 3, while after the completion of the operation the said locking must cease, to enable a new item to be set.

It will be understood that if a multiplication or a division is to be performed, the main spindle, for the purpose of carrying out the calculation, must make a whole number of revolutions, during which the setting mechanism must not be shifted and must be locked. In that case the release of the locking device must not take place. In order to enable this to be done, the sleeve 100 (Figs. 4 and 14) is provided with two guide surfaces 150 and 151 between which a pin 152, arranged below, is adapted to slide. If the said pin 152 is in the position shown in full lines in Fig. 14, no change of the position of the sleeve 100, and therefore also of the operative cam disk 102 can take place during the revolution of the main spindle, and therefore the lever 105 will be brought back 130

to its original position during one calculation as has to be done in the case of an addition. If, however, multiplications or divisions are to be made, the pin 152 is brought into the position shown dotted in Fig. 14. In that case, the pin 152 will coöperate with the cam face 151 in such manner that, after the beginning of the revolution, the sleeve 100 will be moved to the left, so that the full or circular disk 101 will coöperate with the long roller 103, and lock the latter in the position shown in Fig. 13, while at the same time the cam disk 102 will be moved out of reach of the roller 104, so that no return movement to the left can take place by means of that roller. The setting mechanism will therefore remain locked until the pin 152 is again brought into the position shown in Fig. 14, before the beginning of any rotation of the main spindle.

In the case of machines operated by hand, the pin is simply placed in the desired position by means of a suitable handle. If the mechanism is to be used with automatic machines, the arrangement is preferably such that, as soon as the addition key has been depressed, or the slide or carriage of the setting mechanism arrives at its outer right hand position, the pin 152 will be brought thereby into the position shown in Fig. 14, while on a multiplication or division key being depressed, the pin 152 will be brought into the position shown dotted in Fig. 14.

The reciprocation of the oscillating parts 111, 111' can be advantageously utilized for operating a practical zeroizing device. In most cases it will be desirable to operate the zeroizing device of the setting mechanism and thus to bring the keys to their original position, that is to say, in the case of an addition, after one revolution of the main spindle, and in case of a multiplication or division, after the calculation is completed, *i. e.* not until the figure set up has been transferred repeatedly to the counting gears. For that reason, there are secured to the oscillating parts 111, 111' or to the spindle 112 two drivers 170 and 171 (Figs. 3 and 4) which can press upwardly a bar 174 pivoted about screws 173 as soon as the spindle 112 is correspondingly oscillated. The bar 174 then presses the pins 175 secured to the toothed racks 26 already referred to, so that the latter are pushed upward, and their movement results in a backward rotation of the spindles 24 and 30 into their position of rest.

It must be pointed out that the spindle 112 is mounted in the casing in a laterally adjustable manner, so that the drivers 170 and 171 can take up a position outside the sheet metal bar 174, in which case the zeroizing device would not be operative. A lever 180 suitably connected to the sliding part 111, enables the same to be moved by hand, as

soon as it has been moved to the right in Fig. 4. The right or left hand movement (in Fig. 2) of the lever 180 determines the position of the spindle 112, so that such a movement can determine whether the movement of the device is to be effected automatically or by hand. 70

The position of the lever 180 can be fixed by a suitably shaped member which can spring into a suitable recess of the cover of the setting mechanism. Another advantage of the present key mechanism is that, although the setting mechanism is locked during the calculation, the calculator can nevertheless set a fresh item on the keys during 80 the calculation, without any confusion being produced by the uninterrupted, simultaneous, repeated transferring of the figure previously set up to the counting gears. To this end, the resetting spindles 30 are adjustable in their bearings and can be moved to left and right, (Figs. 5 and 1) by means of the same bar 183 in grooves 184. When the setting mechanism is locked at the beginning of the calculation, the stops 186 and 187 secured respectively to the oscillating parts 111 or 111', strike simultaneously the stops 188, and thus shift the bar 183, and consequently all the resetting spindles 30, so far to the left that the pins 31 are out of 90 engagement with the key pins 32 situated above. In this way, there is obtained, on the one hand, the result that during the automatic zeroizing and the consequent rotation of the spindles 30, any keys depressed are 100 not affected, but remain in the depressed position, until the resetting spindles 30 are again in their initial position. As soon, on the other hand as this zeroizing has been effected by the oscillation to the right of the 105 sliding parts 111 and 111', the corresponding stops 190 and 191 will strike the stops 188 of the slide 183 and, thus bring back the same, as well as the spindles 30, to the right, to their normal position, and as the setting 110 mechanism is no longer locked, the resetting spindle 30 will be rotated by the spring 25 in the manner already described, until the rising of a formerly depressed key stops that movement in the usual manner. 115

In order to make the matter clear, the following must be again mentioned: The oscillating parts 111 or 111', at the beginning of a calculation, are moved a little to the left in Figs. 3 and 4 up to the position shown in the same, and lock the setting mechanism for one or several revolutions. After one half of the last revolution of the main spindle during a calculation, the locking is released as described, owing to the rotation of the spindle 112 in a clockwise direction to its extreme right position, and at the same time the automatic zeroizing is effected, whereupon a partial rotation of the spindle 112 to the left takes place, into the initial position, 120 125 130

before the completion of the rotation of the main spindle.

The setting of a figure on the setting mechanism by rotation of the resetting spindle 30 can also be effected automatically according to a figure already indicated on the counting gear for the result. To that end step pulleys 198 (Fig. 1) are connected to the figure disk of the counting gear, against which pulleys can press sliding parts 191 mounted in a horizontally adjustable manner in a bar 192. (Figs. 1 and 17.) With the ends 191' of the said sliding parts slides 193 are adapted to coöperate. The slides 193 are mounted in the following manner: Riveted to the figure wheel 53 and sliding on the resetting spindle 30, but rotating with it is a small cylinder 296 with a worm 299 milled around its surface. The cylinder 296 is disposed within a second cylinder 295 having a groove 294 therein, in which the said slides 193 can move to the right and the left (Fig. 17). The slides are prevented from falling out by means of a ring 297 placed over the cylinder. The slides 193 engage with their pin 298 in the milled worm 299 so that, when the spindle 30 is turned in setting a figure, the slide 193 will be moved to the left (Fig. 17), as this slide with the cylinder 295 is prevented from rotation by the tooth 304 of the cylinder 295 which is positioned by a slide 301.

If the setting of the setting mechanism or of the wheels 53 indicating the key struck, is to be effected in accordance with the figure wheels 8 of the counting gear, a lever 300 (Figs. 1 and 2) will be moved to the left (Fig. 2). This lever 300 is mounted on a slide 301 provided at its end with drivers 302 and 303 (Fig. 2) which can turn the hollow cylinder 295 by means of a tooth 304, so that the slide 193 mounted in the said sleeve, is lowered, and thus brought into contact with the slide 191 while normally it remains in the position shown in Fig. 17 above the end 191' of the slide 191''. At the same time, however, during the movement of the lever 300 to the left, the pivoted double lever 307 (Fig. 2) will be turned, and as the right end of the lever 307 is pivoted as shown in Fig. 2, to a bar 308, the said bar 308 will be pulled to the right in Fig. 2. This bar 308 is normally drawn to the left by means of a spring, and is provided with pins 309 engaging with the oscillating part 310 carrying the previously described locking tooth 22. Owing to the movement of the bar 308 to the right, the said locking teeth are released, and in that way the spindles 24 and 30 are moved by the action of the spring 25, each of the resetting spindles 30 being rotated by the corresponding spring until the slide 193 presses the slide 191 against the stepped wheel 198 which of course allows a different forcing-in of the

slide 191 according to the value of the figure on the corresponding figure disk. In that way it is possible to transfer to the key-mechanism a figure appearing on the counting gear, without, as has been necessary in former constructions, setting the counting gear to zero. 70

Having now particularly described and ascertained the nature of my said invention and in what manner the same is to be performed, I declare that what I claim is: 75

1. In a setting mechanism for multiplying or dividing machines, a main operating shaft, a number of slides or keys, and means for setting up a multiplicand upon said slides or keys and for determining the multiplier by a number of rotations performed by said shaft, in combination with a carriage for determining by its different lateral positions the different digits of the multiplier, a sliding part, and a set of levers adjusted by the means for setting up a multiplicand and connected therewith in such manner that they operate to impart different movements to said sliding part through the 90 medium of said main shaft. 80

2. In a setting mechanism for multiplying or dividing machines, the combination of a main spindle, setting mechanism, a zero setting device for the same, and means for operating the latter after one or several revolutions of said spindle. 95

3. In a setting mechanism for multiplying or dividing machines, the combination of a main spindle, setting mechanism, a locking device for the same, and means for operating the latter after one or several revolutions of said spindle. 100

4. In a setting mechanism, the combination of a set of keys or slides, a spindle, a 105 spring to actuate it, stops on the spindle co-operating with stops on the keys to return the latter and stop the spindle, a feed gear for calculating machines, and means to set the feed gear according to the position of 110 said spindle.

5. In a setting mechanism, in combination of keys, a spindle set to different positions by the actuation of said keys, a spirally grooved cylinder on said spindle, a sliding 115 part, a lever pivoted on said sliding part and adjusted by said spirally grooved cylinder, and means to move the sliding part to different amounts depending upon the position of said lever. 120

6. In a feed gear for calculating machines, a sliding part, an adjustable lever pivoted upon said sliding part, a main spindle, and means to impart different movements to said sliding part depending upon 125 the adjustment of said lever.

7. In a feed gear for calculating machines, the combination of means for setting up a figure, sliding parts, means for imparting different movements to said slid- 130

ing parts depending upon the figure set up, a pinion, two racks fastened upon the sliding part and capable of moving the pinion in opposite directions, and means to move 5 the pinion into engagement with either one of the two racks.

8. In a setting mechanism for calculating machines, the combination of means for setting up a figure, sliding parts, a swinging bar, two levers interposed between said swinging bar and said sliding parts, and means to adjust the levers to impart different movements to the sliding parts according to the figure set up.
- 15 9. In a setting mechanism for multiply-

ing or dividing machines, the combination of a main spindle, setting mechanism, a zero setting device for the same, means for operating the latter after one or several revolutions of said spindle, and means operated 20 at will to render said operating means ineffective.

In testimony whereof I have signed my name to this specification in the presence of two subscribing witnesses, this 14th day of 25 July 1911.

ALEXANDER RECHNITZER.
